UNITED STATES PATENT OFFICE

ANDREW EKMAN, OF GRAND RAPIDS, MICHIGAN, ASSIGNOR TO GRAND RAPIDS BRASS COMPANY, OF GRAND RAPIDS, MICHIGAN

REVERSIBLE LATCH

Application filed April 22, 1929. Serial No. 357,076.

The main object of this invention is to provide a reversible latch having few parts, these parts being simple and economical to produce and easily assembled.

5 A further object is to provide a reversible latch well adapted for use on heavy doors.

Objects pertaining to details and economies of my invention will definitely appear from the description to follow. The invention is 10 defined in the claims.

A structure which embodies the features of my invention is clearly illustrated in the accompanying drawing, in which:

Fig. 1 is an inverted view of my improved 15 latch with the base plate omitted.

Fig. 2 is a detail view mainly in longitudinal section on line 2—2 of Figs. 1 and 3.

Fig. 3 is a fragmentary view on a line corresponding to line 3—3 of Fig. 2.

20 Referring to the drawing, the housing 1 of the embodiment illustrated is a stamping having an opening 2 in its rear wall and an opening 3 in its front wall through which the bolt 4 projects and is adapted to swing. The 25 base plate 5 is housed within or covered by this housing.

The pivot 6 is supported at its upper end by the inturned arm 7 formed by striking in a portion of the rear wall to form the opening 30 2. The bolt 4 is mounted on this pivot with its front end projecting through the opening 3. The front end is provided with a strike or keeper engaging roller 8.

The bolt is longitudinally slotted or 35 recessed at 9 to receive the spring 10 and the inwardly projecting arm 11 of the reciprocating toggle member 12. This toggle member has a longitudinal slot 13 engaging the pivot. The spring 10 is disposed between the pivot 40 and the arm 11 under compression.

The rocking or pivoted toggle member 14 is pivoted at 15 on the reciprocating toggle member 12 and has spaced fulcrum points 16 45 rockingly engaging the front wall of the housing above the opening 3 therein, the front wall of the housing constituting a supporting abutment for the toggle.

The side walls 17 of the housing limit the lateral movement of the pivoted toggle member so that when the bolt is swung on its piv-

ot, the pivot 15 of the pivoted toggle member swings with the bolt, thereby rocking the pivoted toggle member on one of its fulcrum points and subjecting the spring 10 to still further compression, so that when the bolt 55 is released it is again returned to its central position with both fulcrum points of the toggle member bearing against the front wall of the housing.

The structure is very simple and economical 60 in its parts, the parts are strong and durable and easily assembled.

Having thus described my invention what I claim as new and desire to secure by Letters Patent is:

1. In a reversible latch, the combination 70 with a housing, a pivot within said housing, a longitudinally slotted bolt mounted on said pivot, a reciprocating toggle member slotted to embrace said pivot and provided with an arm projecting into said slot in said bolt, a toggle member pivotally mounted on said reciprocating toggle member and provided with a pair of spaced fulcrum points rockingly engaging the front wall of the housing, 75 the side walls of the housing constituting supports for the end of said pivoted toggle member, and a spring disposed in said slot in said bolt between said reciprocating toggle member and said pivot. 80

2. In a reversible latch, the combination 85 with a housing, a pivot within said housing, a longitudinally slotted bolt mounted on said pivot, a reciprocating toggle member slotted to embrace said pivot and provided with an arm projecting into said slot in said bolt, a toggle member pivotally mounted on said reciprocating toggle member and provided with a pair of spaced fulcrum points, and a spring disposed in said slot in said bolt between said reciprocating toggle member and said pivot. 90

3. In a reversible latch, the combination 95 with a housing, a bolt pivotally mounted within said housing for swinging movement, a reciprocating toggle member engaged with said bolt to swing therewith, a second toggle member pivotally mounted on said reciprocating toggle member and provided with spaced fulcrum points rockingly engaging the front wall of said housing, the side wall 100

of the housing constituting supports limiting the lateral movement of said pivoted toggle member, and a spring acting on said reciprocating toggle member to yieldingly hold both fulcrum points of the pivoted toggle member in engagement with their supporting abutments.

4. In a reversible latch, the combination with a housing, a bolt pivotally mounted within said housing for swinging movement, a reciprocating toggle member engaged with said bolt to swing therewith, a second toggle member pivotally mounted on said reciprocating toggle member and provided with spaced fulcrum points, and a spring acting on said reciprocating toggle member to yieldingly hold both fulcrum points of the pivoted toggle member in engagement with their supporting abutments.

5. In a reversible latch, the combination of a support provided with a pivot, a bolt mounted on said pivot, a reciprocating toggle member slotted to engage said pivot and having sliding engagement with said bolt, a second toggle member pivotally mounted on said reciprocating toggle member and provided with a pair of spaced fulcrum points, said support being provided with coacting supporting abutments, and a spring acting on said reciprocating toggle member to urge said pivoted toggle member against its supporting abutments.

6. In a reversible latch, the combination of a support, a bolt mounted on said support for swinging movement, a reciprocating toggle member having sliding engagement with said bolt, a second toggle member pivotally mounted on said reciprocating toggle member and provided with a pair of spaced fulcrum points, said support being provided with coacting supporting abutments, and a spring acting on said reciprocating toggle member to urge said pivoted toggle member against its supporting abutments.

45 In witness whereof I have hereunto set my hand.

ANDREW EKMAN.
